Primary Examiner — Jennifer Rivard(74) *Attorney, Agent, or Firm* — Foley & Lardner LLP**CLAIM**

I claim the ornamental design for a skin removal device, as shown and described.

DESCRIPTION

FIG. 1 is a top, front, right perspective view of an embodiment of the claimed design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof; and,

FIG. 7 is a left elevation view thereof.

The ornamental design which is claimed is shown in solid lines in the drawings. The broken lines in the drawings illustrate unclaimed portions of the article and form no part of the claimed design.
